GAME DEVICE

Filed June 5, 1929

Inventor
F. Lauterbach

By his Attorney Frank Ledermann

UNITED STATES PATENT OFFICE

FREDRIK LAUTERBACH, OF NEW YORK, N. Y.

GAME DEVICE

Application filed June 5, 1929. Serial No. 368,494.

The main object of this invention is to provide a gaming device in which dice are used. The device encloses the dice so that counterfeit dice may not be substituted.

5 Another object of this invention is to provide a device which shakes and shuffles dice in an enclosed visible container upon pressure of a button forming part of the device.

The above and other objects will become 10 apparent in the description below, in which characters of reference refer to like-named parts in the drawing.

Referring briefly to the drawing, Figure 15 1 is a partially sectioned front elevational view of the gaming device, showing the dice supported on the flexing diaphragm which latter is shown in normal and flexed position.

Figure 2 is a top plan view of Figure 1, 20 showing a portion of the crown broken away.

Referring in detail to the drawing, the 25 numeral 10 indicates an inverted ornately formed housing which encloses a chamber 11 having the mechanism therein. The bottom of the housing 10 is completely capped by a disc 12 which has a bounding recess 13 formed thereon. This recess 13 receives the beaded lip 14 of the housing 10, which is provided for the purpose of sealing the device. Within the chamber 11 a pedestal 15

30 is mounted on the disc 12 in some desirable manner. The pedestal 15 has a channel therein which receives a lever 16. Said lever 16 is provided with a pair of opposing pins 17

35 which cradle in slots 18 formed in the upper end of the pedestal 15. One end of the lever 16 has pivotally connected thereto a bar 19 which passes through an opening in the housing 10 in which is mounted a collar 20. The upper end of the bar 19 projects to a position 40 above the housing 10 and is surmounted by a button 21.

The opposite end of the lever 16 has a link 22 pivotally connected thereto. Said link 22 extends vertically upward and is rigidly attached to a slightly dished-out flexing diaphragm 23. The edge of this diaphragm 23 is securely mounted upon a transparent glass crown 24 which encompasses the dice chamber 25. Said diaphragm 23 is adapted to be

flexed from the normal position shown in full lines in Figure 1 to the position shown in broken lines in the same figure, and supports a plurality of dice 26.

The device is adapted to shuffle and shake 55 the dice 26 so that various facets of these dice 26 topple and show various and different values. Shaking of these dice 26 is accomplished by pressure upon the button 21. As said button 21 is depressed, the bar 19 is 60 lowered. With the same movement the one end of the lever 16, to which the link 22 is attached, is raised. This flexes the diaphragm 23 upwardly and, when the critical angle of deflection is reached, which is midway between the normal and flexed position shown in full and broken lines in Figure 1, the diaphragm 23 flexes instantaneously from the intermediate position to the position shown in broken lines in Figure 1 and 65 through this instantaneous shifting of the diaphragm 23, the dice 26 are given a violent lifting, thus toppling and turning these dice 26 and reversing their facets.

The game is used in conventional or special manner, accordingly as desired. 75

It is to be noted that certain changes in form and construction may be made without departing from the spirit and scope of the invention. 80

I claim:

1. In a gaming device, a housing, a transparent crown mounted on said housing, a normally dished-out diaphragm having its edge mounted rigidly in said housing, a link 85 rigid with said diaphragm at the axis of the latter, dice supported on said diaphragm, and means for raising said link to flex said diaphragm.

2. In a gaming device, a housing, a transparent crown mounted on said housing, a normally dished-out diaphragm having its edge mounted rigidly in said housing, a link rigid with said diaphragm, at the axis of the latter, dice supported on said diaphragm, a bar projecting from said housing, a button surmounting said bar exterior of said housing, and means connecting said bar and link for lifting said link upon depression of said bar. 95

3. In a gaming device, a housing, a trans- 100

parent crown mounted on said housing, a normally dished-out diaphragm having its edge mounted rigidly in said housing, a link rigid with said diaphragm at the axis of the latter, dice supported on said diaphragm, a bar projecting from said housing, a button surmounting said bar exterior of said housing, a lever pivotally connected to said bar and said link, and means supporting said lever intermediate its length to permit flexing of said diaphragm

10 upon depression of said bar.

4. In a gaming device, a housing, a transparent crown mounted on said housing, a normally dished-out diaphragm having its edge mounted rigidly in said housing, a link rigid with said diaphragm at the axis of the latter, dice supported on said diaphragm, a bar projecting from said housing, a button surmounting said bar exterior of said housing, a lever pivotally connected to said bar and said link, 15 a slotted pedestal pivotally supporting said lever intermediate its length, said lever shifting in said slot upon the inherent flexing upwardly of said diaphragm after the latter has reached the critical flexing position.

20 25 In testimony whereof I affix my signature.
FREDRIK LAUTERBACH.
